US00D942866S

(12) **United States Design Patent** (10) Patent No.: **US D942,866 S**
Palmer et al. (45) Date of Patent: ** *Feb. 8, 2022

(54) **CONTAINER**

(71) Applicants: **UNILOY, INC.**, Tecumseh, MI (US);
ALTIUM PACKAGING LP, Atlanta, GA (US)

(72) Inventors: **Joey Palmer**, Marietta, GA (US);
James Janeczek, Tecumseh, MI (US);
Robert Spagnoli, Cement City, MI (US)

(73) Assignees: **UNILOY, INC.**, Tecumseh, MI (US);
ALTIUM PACKAGING LP, Atlanta, GA (US)

(*) Notice: This patent is subject to a terminal disclaimer.

(**) Term: **15 Years**

(21) Appl. No.: **29/623,105**

(22) Filed: **Oct. 23, 2017**

Related U.S. Application Data

(60) Division of application No. 29/552,398, filed on Jan. 21, 2016, now Pat. No. Des. 800,567, which is a continuation-in-part of application No. 29/522,745, filed on Apr. 2, 2015, now Pat. No. Des. 749,422.

Primary Examiner — Janice Patyk

(74) Attorney, Agent, or Firm — Barnes & Thornburg LLP

(57) **CLAIM**

The ornamental design for a container, as shown and described.

DESCRIPTION

FIG. 1 is a rear, right side, top perspective view of a container showing our design.

FIG. 2 is a front, right side, bottom perspective view of the container of FIG. 1.

FIG. 3 is a right side view of the container of FIG. 1.

FIG. 4 is a rear view of the container of FIG. 1.

FIG. 5 is a left side view of the container of FIG. 1.

FIG. 6 is a front view of the container of FIG. 1.

FIG. 7 is a top plan view of the container of FIG. 1; and, FIG. 8 is a bottom plan view of the container of FIG. 1.

The broken lines in the figures illustrate the portions of the design that form no part of the claimed design.

1 Claim, 8 Drawing Sheets
